United States Patent Office

Des. 221,875

Patented Sept. 14, 1971

221,875

STATIONARY EXERCISE BICYCLE

David H. Braun, Miami, Fla., assignor to Allied Leisure Industries, Inc., Hialeah, Fla.

Filed May 28, 1970, Ser. No. 23,196

Term of patent 14 years

Int. Cl. D21—03

U.S. Cl. D34—5

FIG. 2

FIG. 1

FIG. 1 is a side elevation, in reduced scale, of a stationary exercise bicycle, showing my new design.

FIG. 2 is a front elevational view thereof.

FIG. 3 is a top plan view thereof.

FIG. 4 is a rear elevational view thereof.

FIG. 5 is a bottom plan view thereof.

I claim:

The ornamental design for a stationary exercise bicycle, as shown.
